UNITED STATES PATENT OFFICE.

WILLIAM OEHLLER, OF PHILADELPHIA, PENNSYLVANIA, ASSIGNOR TO
JOHN BISHOP HALL, OF SAME PLACE.

DESIGN FOR A PATTERN-BOARD.

SPECIFICATION forming part of Design No. 30,296, dated February 28, 1899.

Application filed January 19, 1899. Serial No. 702,724. Term of patent 14 years.

To all whom it may concern:

Be it known that I, WILLIAM OEHLLER, a citizen of the United States, residing at Philadelphia, in the county of Philadelphia and State of Pennsylvania, have invented and produced a new and original Design for Pattern-Boards, of which the following is a specification, reference being had to the accompanying drawings, forming part thereof.

Figure 1 represents a plan view of a pattern-board, showing my new design. Fig. 2 is a sectional view taken on the line X X of Fig. 1.

As shown in the drawings, the leading feature of my design consists of a base or board A, which may be square, rectangular, or other desired shape, having upon its surface a series of blocks B, arranged in rows 1 2 3, and so on, in such manner as to leave spaces C between the adjacent edges of said blocks B.

It will be observed that the blocks B are rectangular in form and are thuswise arranged in vertical lines upon the surface of the board A, and the ends of said blocks in one row are arranged in a horizontal line or

plane with the edges of the blocks in the next succeeding row so that the spaces C in length will be substantially the same length as the blocks B. It will also be observed that the disposition of the blocks B horizontally is such that spaces D will be left between the side edges thereof and that at the outer rows of said blocks B smaller blocks E are placed, the lower edges of which lie in a horizontal line or plane with the ends of the outermost rows, leaving open spaces F, as shown.

The board A at or near its ends is provided with rails G, the spaces between which and the side edges of the adjacent blocks B being the same as the spaces F between each row of blocks.

Having thus described my invention, what I claim as new, and desire to secure by Letters Patent, is—

The design for a pattern-board, substantially as herein shown and described.

WILLIAM OEHLLER.
